UNITED STATES PATENT OFFICE.

FRANZ ANTON HUBBUCH, OF FURTWANGEN, GERMANY.

WATER-METER.

SPECIFICATION forming part of Letters Patent No. 557,820, dated April 7, 1896.

Application filed July 6, 1895. Serial No. 555,167. (No model.) Patented in Germany December 16, 1894, No. 83,598; in Switzerland April 15, 1895, No. 10,298; in Belgium April 22, 1895, No. 115,236; in France April 29, 1895, No. 246,984; in Hungary May 2, 1895, No. 2,682; in Austria May 14, 1895, No. 1,700; in England June 7, 1895, No. 11,224, and in Italy June 30, 1895, XXX, 38,982, LXXVI, 281.

To all whom it may concern:

Be it known that I, FRANZ ANTON HUBBUCH, of Furtwangen, in the Grand Duchy of Baden and German Empire, have invented a certain new and useful Improvement in Water-Meters, (for which I have obtained Letters Patent in Austria, No. 1,700, dated May 14, 1895; in Hungary, No. 2,682, dated May 2, 1895; in Belgium, No. 115,236, dated April 22, 1895; in France, No. 246,984, dated April 29, 1895; in Great Britain, No. 11,224, dated June 7, 1895; in Switzerland, No. 10,298, dated April 15, 1895; in Italy, XXX, 38,982, LXXVI, 281, dated June 30, 1895, and in Germany, No. 83,598, dated December 16, 1894,) of which the following is a specification, reference being had to the accompanying drawings.

This invention relates to water-meters.

The adjustment of water-meters, for securing a correct measuring action of the same, is at times a very tedious matter. The means heretofore devised for rendering such adjustment possible and for effecting the said adjustment with promptness and dispatch whenever required were in most cases not based upon scientific principles and would very often impair the sensitiveness of the water-meters. The said means or devices are usually provided within the water-inlet, and they would thus act to reduce the speed of movement of the water previously to its being measured, or they would allow a portion of the water to pass through the measuring-chamber of the meter without being measured at all. It is obvious that a device or arrangement which would admit of a gaging or adjusting of the action by regulating the flow at the discharge would under all circumstances be preferable to the devices or arrangements heretofore employed, as referred to above.

The object of this invention is to provide a construction of water-meter having this improved mode of adjustment; and the invention therefore consists in the arrangement and combination of parts more fully hereinafter described, and shown in the accompanying drawings, in which—

Figure 1 is a central vertical section on the

line A B of Fig. 2 of a water-meter provided with my improvement. Fig. 2 is a horizontal section on the line C D of Fig. 1. Fig. 3 is a horizontal section on the line E F of Fig. 1 with the winged wheel removed. Fig. 4 is a sectional elevation of a detail on the line G H of Fig. 3.

The general construction of a wheel water-meter being well known does not require to be particularly here described.

The water freely enters the measuring-chamber *z* in a tangential direction through the openings *m m*, thereby imparting rotary movement to the shaft *W* of the measuring-wheel *f*. (See Fig. 1.) By means of curved channels *k k*, provided in the inner top portion, and by similar channels *p p*, provided in the bottom of the casing, the measured water is conducted toward the said shaft and caused to pass through the aperture *d* and openings *n n* to the place whence it is taken for use. The channels *k k*, as well as the channels *p p*, are of uniform cross-section throughout. In being driven from the peripheral portion of the measuring-casing toward the aperture *d* the water, by its swell, acts to disturb the free movement of the measuring-wheel.

It is obvious that by allowing a portion of the measured water to escape into the regular discharge-conduit near the circumferential portion of the measuring-casing the measuring-wheel may be caused to rotate more freely, and that the result of the measurement may thus be altered. To this end holes *b b* are bored in the raised portions formed by and between each two channels *k k*, (see Fig. 1,) and above the said holes is provided a ring *S*, the latter resting in a correspondingly-shaped annular recess and being provided with openings *a a*, corresponding with the holes *b b* above referred to. By means of an arm or index *X*, provided on the said ring, (see Fig. 2,) the latter may be rotated more or less, so as to alter the positions of the openings *a a* with regard to the holes *b b*, and the latter may thus either be closed entirely or opened to any desired width. It will thus be seen that by a suitable adjustment of the position of the said ring, which I shall hereinafter re-

fer to as the "gaging-ring," a portion of the measured water, after having taken part in the movement of the winged measuring-wheel, may be discharged into the conduit without being forced through the aperture d , and without, on its way to this aperture, hindering the movement of the winged measuring-wheel.

If the wheel-train of the counting mechanism, which is in the usual and well-known manner inclosed in the chamber M , and therefore not shown in the drawings, is so arranged that in a particular apparatus the result of the measurement would differ by about ten per cent., then this may be easily corrected by moving the arm or index X , and thereby turning the gaging-ring S . The said ring is retained in its position by the eight feet forming the connection between the chamber of the counting mechanism and the measuring-casing.

A rough or preliminary adjustment may also be effected by means of the ring u , the latter being shown in position within the water-meter casing in Fig. 3, while Fig. 4 shows the said ring removed. By turning this ring a resistance may be introduced in the channels $p p$, so that the flow of water toward the center will thereby be impeded. The channels $p p$, provided in the bottom h of the casing, may either be curved in the direction of the flow of water or in the opposite direction. By this means and by selecting the proper degree of curvature for the channels I may cause the water-meter either to lag behind gradually or to advance in the indication from the largest to the smallest passage of water.

Having thus fully described my invention,

what I desire to claim and secure by Letters Patent is—

1. In a water-meter, the combination of the measuring-casing z having tangential inlet-openings m curved channels k in the inner top portion of said casing with vertical passages b between said channels, a rotatable ring s arranged in the cover of the measuring-casing above the passages b and provided with openings a , and the measuring-wheel f having its shaft w extended through an aperture d communicating with outlets n , substantially as described. 40 45 50

2. In a water-meter, the combination of the measuring-casing z having tangential inlets m , curved passages p in its bottom controlled by a perforated adjustable ring u , and provided in the top with a central aperture d , 55 curved channels k and vertical passages t intermediate the said curved channels, a perforated rotatable ring s to control said vertical passages b , and the measuring-wheel f , substantially as described. 60

3. In a water-meter a number of curved channels, such as $p p$, provided in the bottom of the measuring-casing, and an adjustable ring, such as u , capable of being rotated with relation to the said channels, substantially as 65 and for the purpose set forth.

In testimony whereof I have signed my name to this specification in the presence of two subscribing witnesses.

FRANZ ANTON HUBBUCH.
